To all whom it may concern:

Be it known that we, Bennie L. Berg and Phyllis R. Berg, citizens of the United States, residing at Madison, in the county of Dane and State of Wisconsin, have invented a new, original, and ornamental Design for a Display Cabinet, of which the following is a specification, reference being had to the accompanying drawings forming a part thereof.

Figure 1 is a perspective view of a display cabinet embodying our new design, viewing the same from the right front corner;

Figure 2 is a perspective view looking at the display cabinet from the right rear corner;

Figure 3 is a front view thereof; and

Figure 4 is a side view of the display cabinet. The dominant features of our design reside in those portions thereof shown in full lines.

We claim:

The ornamental design for a display cabinet, as shown.
